UNITED STATES PATENT OFFICE

WALTER G. POTTER, OF CHICAGO, ILLINOIS.

PROOF-PRESS.

957,373.

Specification of Letters Patent. Patented May 10, 1910.

Application filed June 17, 1909. Serial No. 502,780.

To all whom it may concern:

Be it known that I, WALTER G. POTTER, a citizen of the United States, residing at Chicago, in the county of Cook and State 5 of Illinois, have invented certain new and useful Improvements in Proof-Presses, of which the following is a specification.

The object of this invention is to produce a proof press of simple construction which 10 may be conveniently and rapidly operated.

In the accompanying drawings, Figure 1 is a side elevation of a proof press embodying the features of my invention. Fig. 2 is a top plan view thereof. Fig. 3 is a fragmental longitudinal vertical central section through the machine, taken upon the plane of dotted line 3-3 of Fig. 4. Fig. 4 is a transverse vertical section through the machine. Fig. 5 is a fragmental view of a 20 paper stop.

The frame 1 may be of any suitable construction. It is herein shown as comprising a table 2, legs 3, and braces 4. Extending longitudinally of the table 2 are tracks 25 or rails 5 upon which is slidably mounted a form bed 6. At the ends of the form bed are flanges 7, either or both of which may be removable for convenience in placing upon the form bed the matter from which 30 an impression is to be taken. Two side flanges or rails 8 extend longitudinally of the bed and project some distance beyond one end of the latter. Rigidly attached to the outer sides of the rails 8 are rack bars 9.

Two brackets 10 are rigidly fixed to opposite sides of the table 2 and have bearings 11 at their upper ends to receive eccentric bearing blocks 12. In said bearing blocks is rotatably supported a shaft 13 on which 35 is rigidly fixed an impression cylinder 14 having gear rings 15 fixed upon its ends in position to mesh with the racks 9. An opening 16 (Fig. 3) is formed in the periphery of the cylinder 14. A packing 17 of paper 40 or other suitable material is secured upon the periphery of the cylinder 14 by means of clamping plates 18 and 19 and screws 20. The clamping plate 19 may have projections 45 21 thereon, as shown in Fig. 5, to form stops 50 for one end of the sheet of paper. In order to clamp said end of the paper, I provide a rock shaft 22 extending longitudinally of the cylinder within the opening 16, said shaft carrying a number of spring fingers 55 23 extending into position to clamp the paper between their outer ends and the pe-

riphery of the roller adjacent to the clamping plate 19. Upon one end of the shaft 22 is fixed an operating arm 24. A spring 25 attached at one end to the free end of said 60 arm and at its other end to the side of the cylinder 14 tends to rock the shaft 22 to clamp the paper.

A crank 26 fixed to one end of the shaft 13 provides means for rotating the impression cylinder 14 and reciprocating the form bed 6.

To the eccentric bearing blocks 12 are fixed arms 27, the outer ends of which are connected by means of links 28 with arms 29 65 fixed upon a rock shaft 30. Stops 31 supported upon the braces 4 limit the downward movement of the eccentric-operating arms 27. A treadle 32 fixed to the rock shaft 30 provides means for rocking the arms 27 and 70 the eccentric bearing blocks 12 to raise the cylinder 14 out of position to contact with a form placed upon the bed 6, but not far enough to disengage the gears 15 from 75 racks 9. Suitable means, such as a spring 33, is provided for holding the cylinder 14 in its lowered position during the taking of an impression. Coöoperating stops 34 and 35 upon the cylinder 14 and one of the brackets 10, respectively, limit the rotary movement 80 of the cylinder and the reciprocatory movement of the form bed in either direction.

36 is a bar extending from one of the brackets 10 to the other and serving to hold up the end of the paper so that said end 90 shall not drop onto the form and cause a slur.

When a proof is to be taken, the crank 26 is rotated in the direction of the arrow in Fig. 1 until the stop 34 engages the stop 35, when the form bed will be at the right-hand limit of its movement and the paper clamp will be at the right-hand side of the cylinder 14. One end of a sheet of paper is then 100 placed in the clamp, with the sheet lying across the top of the cylinder. The crank 26 is then rotated in the reverse direction, rotating the impression cylinder, moving the form bed to the left, and drawing the sheet of paper between the cylinder and the form on the bed. When the sheet has passed between the cylinder and the form it may be removed by opening the paper clamp. The operator then raises the cylinder by means 105 of the treadle 32 and returns the cylinder and the form bed to the starting position by rotating the crank 26.

The paper clamp is opened by raising the arm 24.

The matter from which an impression is to be taken may be secured upon the bed 6 in any common or preferred way, or may be left loose thereon.

I claim as my invention:

1. In a proof press, in combination, a table; a form bed slidable on said table; a bracket secured to each side of said table; bearing blocks rotatably mounted in said brackets; an impression cylinder having its journals eccentrically mounted in said bearing blocks; a driving connection between said cylinder and said form bed; stop means on one of said brackets; means on said cylinder arranged to engage said stop means to limit the rotation of the cylinder and the movement of the form bed; an arm fixed on each of said bearing blocks, said arms being arranged to rotate said blocks to move said impression cylinder toward and away from the form bed; means tending to hold said arms in position to hold the impression cylinder on the form bed; and means for moving said arms in the opposite direction.

2. In a proof press, in combination, a table; a form bed slidable on said table and having a rack bar secured thereto; a bracket

secured to each side of said form bed and having bearing openings therein; bearing blocks rotatably mounted in said openings; an impression cylinder having journals eccentrically mounted in said bearing blocks; a gear wheel on said cylinder arranged to mesh with the rack on said form bed; a projection on one of said brackets; means on said cylinder arranged to engage said projection to limit the rotation of said cylinder and the sliding movement of the form bed; an arm fixed to each of said bearing blocks, said arms being arranged to rotate said blocks to move said impression cylinder away from the form bed; a rock shaft mounted in said table; arms fixed on said rock shaft; links connecting the free ends of said arms with the first mentioned arms; a treadle fixed on said rock shaft for moving said arms in the direction to raise said impression cylinder off the form bed; and a spring engaging one of said arms and tending to hold it in position to keep said cylinder in contact with the form bed.

WALTER G. POTTER.
